CLAIM

The ornamental design for a modular swing, substantially as shown and described.

DESCRIPTION

FIG. 1 is a first perspective view of a modular swing according to the design.

FIG. 2 is a second perspective view of the swing of FIG. 1.

FIG. 3 is a front view of the swing of FIG. 1.

FIG. 4 is a back view of the swing of FIG. 1.

FIG. 5 is a first side view of the swing of FIG. 1.

FIG. 6 is a second side view of the swing of FIG. 1.

FIG. 7 is a top view of the swing of FIG. 1; and,

FIG. 8 is a bottom view of the swing of FIG. 1.

The broken line portions of the drawing figures are included to show portions of the article or environment that are not part of the claimed design.

1 Claim, 6 Drawing Sheets
